FOREIGN PATENT DOCUMENTS

WO WO2015195170 12/2015

Primary Examiner — Gloria M Hale

(57) **ABSTRACT**

A shower brassiere for protecting surgical wounds and wound dressings from water while the wearer showers includes a garment body which configured to be worn around a chest of the wearer. The garment body has a generally tubular shape with a top end and a bottom end which are open to an interior space of the garment body. The garment body also comprises a water impermeable material. Drawstrings are attached to the garment body which are operable to cinch the garment body against the wearer's body to seal an interior of the garment body from the surrounding atmosphere.

BACKGROUND OF THE INVENTION

(1) Field of the Invention

The disclosure relates to brassieres and more particularly pertains to a new brassiere for protecting surgical wounds and wound dressings from water while the wearer showers.

**(2) Description of Related Art Including
Information Disclosed Under 37 CFR 1.97 and
1.98**

Following surgical procedures such as mastectomies and lumpectomies, patients are faced with the challenge of bathing or showering without causing water, soap, and other contaminants from interfering with wound dressings or entering healing wounds. The prior art discloses brassieres for use after such surgical procedures, but many are aimed merely at providing support for drainage tubes or other articles without providing a solution that enables the patient to bathe or shower without risking infection or damaging wound dressings.

U.S. Pat. No. 10,194,701 discloses a brassiere which is water impermeable, includes a cavity for storing a drainage bulb or tube, and has a sealing strip for sealing off an area of the patient's body to prevent entry of water and other contaminants into wounds and wound dressings. However, the garment disclosed by the patent does not include features which allow the patient to adjust the seal against the patient's body and requires the garment to apply a compressive force when worn on the patient's body in areas which may cause discomfort for the patient.

The prior art fails to describe a brassiere with a generally tubular shape that includes drawstrings to seal water and soap from entering an interior of the brassiere. The prior art also fails to disclose such a brassiere which is shaped to avoid compression against the patient's breasts or nearby

areas which may have healing wounds or are otherwise sensitive. The prior art also does not address such a brassiere which forms an aperture to facilitate access to the interior of the brassiere when the brassiere is worn. Such features 5 address a need not met by the prior art.

BRIEF SUMMARY OF THE INVENTION

An embodiment of the disclosure meets the needs presented above by generally comprising a garment body which 10 configured to be worn around a chest of a user. The garment body has a generally tubular shape with a top end and a bottom end which are open to an interior space of the garment body. The garment body also comprises a water 15 impermeable material. A top drawstring is coupled to the garment body proximate the top end and is cinchable against the garment body to constrict the top end of the garment body.

There has thus been outlined, rather broadly, the more 20 important features of the disclosure in order that the detailed description thereof that follows may be better understood, and in order that the present contribution to the art may be better appreciated. There are additional features of the disclosure that will be described hereinafter and which will 25 form the subject matter of the claims appended hereto.

The objects of the disclosure, along with the various 30 features of novelty which characterize the disclosure, are pointed out with particularity in the claims annexed to and forming a part of this disclosure.

**BRIEF DESCRIPTION OF SEVERAL VIEWS OF
THE DRAWING(S)**

The disclosure will be better understood and objects other 35 than those set forth above will become apparent when consideration is given to the following detailed description thereof. Such description makes reference to the annexed drawings wherein:

FIG. 1 is a perspective view of a shower brassiere 40 according to an embodiment of the disclosure.

FIG. 2 is a perspective view of an embodiment of the disclosure.

FIG. 3 is a front view of an embodiment of the disclosure.

FIG. 4 is a side view of an embodiment of the disclosure.

FIG. 5 is a cross-section view of an embodiment of the disclosure taken from Line 5-5 in FIG. 3.

FIG. 6 is an in-use view of an embodiment of the disclosure.

**DETAILED DESCRIPTION OF THE
INVENTION**

With reference now to the drawings, and in particular to FIGS. 1 through 6 thereof, a new brassiere emgarment 55 bodying the principles and concepts of an embodiment of the disclosure and generally designated by the reference numeral 10 will be described.

As best illustrated in FIGS. 1 through 6, the shower brassiere 10 generally comprises a garment body 12 configured to be worn around a chest 80 of a user. The garment body 12 has a generally tubular shape with a top end 14 and a bottom end 16 which are open to an interior space 18 of the garment body 12. The garment body 12 comprises a water impermeable material such as vinyl, polypropylene, 60 polycarbonate, or the like. The garment body 12 defines a pair of recesses 28 on an interior side 20 and a front portion 24 of the garment body 12. The recesses 28 are laterally

spaced from each other and are sized to accommodate the user's breasts **82**. In some embodiments, a single recess **28** may be used to accommodate both breasts **82**. Or, in similar manner, the garment body **12** may be generally wider in a central portion of the garment body **12** between the top end **14** and the bottom end **16**. The garment body **12** is shaped as such in order to be worn around the chest **80** without compressing the user's breasts **82** or other portions of the user's body which are located between the top end **14** and the bottom end **16** of the garment body **12**. In some embodiments, portions or all of the garment body **12** may be transparent, which may facilitate monitoring wounds, wound dressings, drainage tubes, and other articles in the interior space **18** of the garment body **12** when worn by the user. In some embodiments, ornamental designs may be printed or otherwise included on the garment body **12**.

The garment body **12** has a break **36** therein which defines a pair of end edges **37** of the garment body **12**. The end edges **37** are couplable together via a connector **38** to define the generally tubular shape. The connector **38** includes a pair of mating members **40**, wherein each mating member **40** is mounted to and extends along an associated one of the end edges **37** of the garment body **12**. The mating members **40** couple with each other to form a seal to prevent water, cleaning fluids, and the like from passing through to the interior space **18** of the garment body **12**. The connector **38** comprises a hook-and-loop fastener but may but may comprise a zipper, snap buttons, or any other suitable fastener and may also include gaskets or other sealing devices to prevent the fluids from passing through the connector.

A pair of pockets **32** is mounted to the interior side **20** of the garment body **12**. Each pocket **32** is positioned in an associated one of the pair of recesses **28** of the garment body **12** and has an opening **34** generally facing a same direction as the top end **14** of the garment body **12**. The pockets **32** may be used to store drainage tubes or other parts of a wound dressing.

A top drawstring **42** and a bottom drawstring **44** are coupled to the garment body **12** proximate the top and bottom ends **14**, **16** respectively. The drawstrings **42**, **44** are cinchable against the garment body **12** to constrict the ends **14**, **16** of the garment body **12**, against the user **78**. The drawstrings **42**, **44** comprise a stretchable material such that they may be pulled against the user's **78** body without cutting uncomfortably into the user's **78** skin and to keep the ends **14**, **16** of the garment body **12** cinched against the user's **78** body when the user **78** maneuvers the user's **78** body.

The top and bottom drawstrings **42**, **44** extend through a top channel **50** and a bottom channel **52** respectively, each of which extends circumferentially with respect to the garment body **12**. The channels **50**, **52** may be formed by tubular segments of the garment body **12**, by layers of material which are stitched together on opposite sides of the channels **50**, **52**, or by any other suitable means. The garment body **12** also defines a top slot **54** which extends through an exterior side **22** of the garment body **12** on the front portion **24** into the top channel **50** and a bottom slot **56** which extends through the exterior side **22** into the bottom channel **52**. End segments **46**, **48** of the drawstrings **42**, **44** protrude forwardly from the garment body **12** through their respective slots **54**, **56**.

A top cord lock **58** and a bottom cord lock **60** are slidably mounted to the end segments **46**, **48** of the top and bottom drawstrings **42**, **44** respectively. The end segments **46**, **48** may be pulled through the respective cord locks **58**, **60** to cinch the respective drawstrings **42**, **44**. The cord locks **58**,

60 may then be operated to secure the drawstrings **42**, **44** in a cinched state. One of the end segments **46**, **48** may be knotted in each of the top and bottom drawstrings **42**, **44** so that the respective cord lock **58**, **60** is retained on the respective drawstring **42**, **44**. The other end segment **46**, **48** of each drawstring **42**, **44** may then be threaded through the respective cord lock **58**, **60** when the user **78** is ready to tighten the drawstring **42**, **44**.

Each cord lock **58**, **60** comprises a receiver **62**, **64** and a button **66**, **68** which is slidably mounted in the receiver **62**, **64**. The button **66**, **68** and the receiver **62**, **64** form a gap therebetween through which the end segments **46**, **48** of the respective drawstring extend, and the button **66**, **68** is biased via a spring or other similar member to close the gap, thereby clamping the drawstring. Other locking devices may be used, including any of a variety of clamping devices or other fasteners. In some embodiments, the end segments **46**, **48** may be tied together to secure the respective drawstring in a cinched state. Other cinching devices also may be used, such as adjustable straps with buckles or the like.

A top seal **70** and a bottom seal **72** are coupled to the interior side **20** of the garment body **12** proximate the top and bottom ends **14**, **16** respectively. Each seal **70**, **72** comprises a resilient material such as rubber, silicone, or the like, such that when the seal is constricted against the user's **78** body, the seal conforms to the user's **78** body to seal the interior space **18** of the garment body **12** from the surrounding atmosphere. The top seal **70** is positioned between the top end **14** of the garment body **12** and the top drawstring **42**. The bottom seal **72** is positioned between the bottom end **16** of the garment body **12** and the bottom drawstring **44**. In other embodiments, the top seal **70** may be positioned inwardly of the top drawstring **42**, and the bottom seal **72** may be positioned inwardly of the bottom drawstring **44**.

A pair of shoulder straps **74** is coupled to the garment body **12** at the top end **14**. The shoulder straps **74** are laterally spaced from each other, and each shoulder strap **74** is coupled to and extends between a back portion **26** of the garment body **12** and the front portion **24** at the top end **14**. Each shoulder strap **74** includes a slider **76** for adjusting a length of the shoulder strap **74**.

In use, the user **78** wears the shower brassiere **10** before showering to prevent water from interfering with wounds or wound dressings on the user's **78** chest **80** or breasts **82**. The garment body **12** is placed around the user's **78** chest **80**, and the recesses **28** are positioned to receive the user's **78** breasts **82** therein. When donning the shower brassiere **10**, the user **78** may disconnect the connector **38** and wrap the garment body **12** around the user's **78** chest **80** rather than sliding into the interior space **18** of the garment body **12** through the bottom end **16**. Then the shower brassiere **10** may be secured on the user's **78** chest **80** by reconnecting the connector **38**.

The shoulder straps **74** extend over the user's **78** shoulders **84** and may be adjusted in length as needed to position the garment body **12** as desired. The user **78** may place drainage tubes or other articles in the pockets **32**. The drawstrings **42**, **44** are cinched to press the seals **70**, **72** into the user's **78** body, sealing the interior space **18** of the garment body **12** from the surrounding atmosphere. The user **78** may then shower as normal while preventing any water from interfering with wounds or wound dressings on the user's **78** body.

With respect to the above description then, it is to be realized that the optimum dimensional relationships for the parts of an embodiment enabled by the disclosure, to include variations in size, materials, shape, form, function and manner of operation, assembly and use, are deemed readily

apparent and obvious to one skilled in the art, and all equivalent relationships to those illustrated in the drawings and described in the specification are intended to be encompassed by an embodiment of the disclosure.

Therefore, the foregoing is considered as illustrative only of the principles of the disclosure. Further, since numerous modifications and changes will readily occur to those skilled in the art, it is not desired to limit the disclosure to the exact construction and operation shown and described, and accordingly, all suitable modifications and equivalents may be resorted to, falling within the scope of the disclosure. In this patent document, the word "comprising" is used in its non-limiting sense to mean that items following the word are included, but items not specifically mentioned are not excluded. A reference to an element by the indefinite article "a" does not exclude the possibility that more than one of the element is present, unless the context clearly requires that there be only one of the elements.

I claim:

1. A shower brassiere comprising:

a garment body configured to be worn around a chest of a user, the garment body having a generally tubular shape with a top end and a bottom end which are open to an interior space of the garment body, the garment body comprising a water impermeable material; a top drawstring coupled to the garment body proximate the top end, the top drawstring being cinchable against the garment body to constrict the top end of the garment body; and a top seal coupled to an interior side of the garment body proximate the top end, the top seal extending circumferentially with respect to the garment body, the top seal comprising a resilient material configured to seal against the user inhibiting fluid to pass between the user and the top seal.

2. The brassiere of claim 1, wherein the top drawstring comprises a stretchable material.

3. The brassiere of claim 1, wherein the top drawstring extends through a top channel defined by the garment body which extends circumferentially with respect to the garment body, a pair of end segments of the top drawstring extending forwardly with respect to the garment body out of the top channel via a top slot defined by the garment body.

4. The brassiere of claim 1, further comprising a top cord lock operable to secure the top drawstring in a selected position with respect to the garment body, the top cord lock being slidably mounted on each of a pair of end segments of the top drawstring.

5. The brassiere of claim 1, further comprising a bottom drawstring coupled to the garment body proximate the bottom end, the bottom drawstring being cinchable against the garment body to constrict the bottom end of the garment body.

6. The brassiere of claim 5, wherein the bottom drawstring comprises a stretchable material.

7. The brassiere of claim 5, wherein the bottom drawstring extends through a bottom channel defined by the garment body which extends circumferentially with respect to the garment body, a pair of end segments of the bottom drawstring extending forwardly with respect to the garment body out of the bottom channel via a bottom slot defined by the garment body.

8. The brassiere of claim 5, further comprising a bottom cord lock operable to secure the bottom drawstring in a selected position with respect to the garment body, the bottom cord lock being slidably mounted on each of a pair of end segments of the bottom drawstring.

9. The brassiere of claim 5, further comprising a bottom seal coupled to an interior side of the garment body proximate the bottom end, the bottom seal extending circumferentially with respect to the garment body, the bottom seal comprising a resilient material configured to seal against the user.

10. The brassiere of claim 1, wherein the garment body defines a recess on an interior side and a front portion of the garment body.

11. The brassiere of claim 1, wherein the garment body defines a pair of recesses on an interior side and a front portion of the garment body, the recesses being laterally spaced from each other.

12. The brassiere of claim 10, further comprising a pair of pockets mounted to the interior side of the garment body, each pocket being positioned in an associated one of the pair of recesses of the garment body, each pocket having an opening generally facing a same direction as the top end of the garment body.

13. The brassiere of claim 1, further comprising a pocket mounted to an interior side of the garment body.

14. The brassiere of claim 1, wherein the garment body has a break therein which defines a pair of end edges of the garment body, the end edges being couplable together to define the generally tubular shape.

15. The brassiere of claim 14, further comprising a connector coupled to the garment body and configured to couple the end edges of the garment body together, the connector comprising a pair of mating members, each mating member of the pair of mating members being coupled to an associated end edge of the pair of end edges.

16. The brassiere of claim 15, wherein the mating members form a seal with each other when coupled together.

17. The brassiere of claim 1, further comprising a pair of shoulder straps coupled to the garment body, the pair of shoulder straps being laterally spaced from each other, each shoulder strap being coupled to and extending between a back portion of the garment body and the front portion at the top end.

18. The brassiere of claim 17, wherein each shoulder strap is adjustable in length.

19. A shower brassiere comprising:
a garment body configured to be worn around a chest of a user, the garment body having a generally tubular shape with a top end and a bottom end which are open to an interior space of the garment body, the garment body comprising a water impermeable material, the garment body defining a pair of recesses on an interior side and a front portion of the garment body, the recesses being laterally spaced from each other, the garment body having a break therein which defines a pair of end edges of the garment body, the end edges being couplable together to define the generally tubular shape;

a top drawstring coupled to the garment body proximate the top end, the top drawstring being cinchable against the garment body to constrict the top end of the garment body, the top drawstring comprising a stretchable material, the top drawstring extending through a top channel defined by the garment body which extends circumferentially with respect to the garment body, a pair of end segments of the top drawstring extending forwardly with respect to the garment body out of the top channel via a top slot defined by the garment body;

a top cord lock operable to secure the top drawstring in a selected position with respect to the garment body, the

top cord lock being slidably mounted on each of the pair of end segments of the top drawstring;
 a bottom drawstring coupled to the garment body proximate the bottom end, the bottom drawstring being cinchable against the garment body to constrict the bottom end of the garment body, the bottom drawstring comprising the stretchable material, the bottom drawstring extending through a bottom channel defined by the garment body which extends circumferentially with respect to the garment body, a pair of end segments of the bottom drawstring extending forwardly with respect to the garment body out of the bottom channel via a bottom slot defined by the garment body;
 a bottom cord lock operable to secure the bottom drawstring in a selected position with respect to the garment body, the bottom cord lock being slidably mounted on each of the pair of end segments of the bottom drawstring;
 a top seal coupled to the interior side of the garment body proximate the top end, the top seal extending circumferentially with respect to the garment body, the top seal comprising a resilient material configured to seal against the user inhibiting fluid to pass between the user and the top seal, the top seal being positioned between the top end of the garment body and the top drawstring;
 a bottom seal coupled to the interior side of the garment body proximate the bottom end, the bottom seal

5

10

15

20

25

extending circumferentially with respect to the garment body, the bottom seal comprising a resilient material configured to seal against the user, the bottom seal being positioned between the bottom end of the garment body and the bottom drawstring;
 a pair of pockets mounted to the interior side of the garment body, each pocket being positioned in an associated one of the pair of recesses of the garment body, each pocket having an opening generally facing a same direction as the top end of the garment body; a connector coupled to the garment body and configured to couple the end edges of the garment body together, the connector comprising a pair of mating members, each mating member of the pair of mating members being coupled to an associated end edge of the pair of end edges, the mating members forming a seal with each other when coupled together, the connector comprising a hook-and-loop fastener; and
 a pair of shoulder straps coupled to the garment body, the pair of shoulder straps being laterally spaced from each other, each shoulder strap being coupled to and extending between a back portion of the garment body and the front portion at the top end, each shoulder strap including a slider for adjusting a length of the shoulder strap.
